JOHN M. SCHILLING AND WILLARD G. SCHILLING, OF LIMA, OHIO.

CARRIER FOR BOTTLE COOLERS.

Application filed November 7, 1927. Serial No. 231,530.

Our invention relates to an improved construction of bottle carrier for use in bottle coolers or refrigerators, by means of which a plurality of bottles of drinks to be cooled may 5 be placed in the carrier and passed by it through a cooling or refrigerating zone, the number of bottles preferably being such that each bottle may be in the cooling zone a sufficient length of time in the usual operation 10 of the device, to thoroughly chill the contents of the bottle.

Our invention provides for the making of a carrier of the kind referred to, from two sheets of metal similarly or identically 15 formed so that when placed together, a plurality of radial compartments is formed for receiving the neck portions of the bottles to be handled by the carrier, the radial depth of each compartment being preferably such that 20 the bottom portion of each bottle preferably projects substantially beyond the outer edge of the carrier to permit convenient handling of the bottles. The bottle compartments of our improved carrier are each tapered from 25 near the outer portion of the carrier to the inner portion of the carrier, at such an angle that the tapered portions together substantially fill the entire angular extent of the carrier, the tapered portions being separated 30 from each other by the minimum amount required for the forming tools to form the tapered portions of the compartments, and the angle of taper of each compartment being preferably such an amount that practically 35 all styles and shapes of bottles commonly employed for soft drinks can be accommodated by the carrier, whether the necks be long and slender in which event the caps engage an abutment of one kind or another at the inner 40 portion of the bottle compartments, or blunt at their neck portions and engage the taper of the compartments at one point or another depending upon the degree of bluntness of the necks.

45 Our improved carrier construction is particularly adapted for use in connection with the bottle cooler construction shown in pending application Serial No. 220,896, and since our present invention is confined to the 50 carrier construction itself, the construction of an entire refrigerator or bottle cooler is not illustrated herein.

Our invention will best be understood by reference to the accompanying drawings

showing a preferred embodiment thereof, in 55 which

Fig. 1 shows our improved carrier in side elevation,

Fig. 2 is a sectional view of the parts shown 60 in Fig. 1 taken along the line 2—2,

Fig. 3 shows our improved carrier in a view similar to Fig. 1 to a reduced scale, with bottles in the carrier compartments and illustrates diagrammatically the meaning for 65 holding the bottles in the compartments in use,

Fig. 4 is a plan view of a part of the structure shown in Fig. 1 showing one of the bottle compartments, and

Fig. 5 shows in a view similar to Fig. 2 a 70 part of the carrier construction illustrating a modified construction of the central part of the carrier.

Similar numerals refer to similar parts 75 throughout the several views.

As shown in Figs. 1, 2 and 4, our carrier consists of two annular sheets of metal 10 and 11, having at intervals distended portions 12 and 13 formed from them so that said 80 distended portions together form bottle compartments when the sheets 10 and 11 are placed together, each of these compartments being substantially cylindrical for a short distance from the outer periphery of the carrier, from which the compartment is of conical 85 conformation to the inner edges of the sheets or disks 10 and 11. The inner diameter of the disks 10 and 11 is such that bottles with long slender necks will have their caps 90 substantially in line with the inner edges of said disks when such bottles are in the carrier in proper position to be moved thereby, with a part of the body portion of the bottle in the outer portion of the compartment, as illustrated for the bottle 14 in Fig. 2. The taper 95 of the conical portion of the compartment is such that for a bottle of blunt construction at its neck end, the shoulder portion of the bottle adjacent the neck will engage the conical wall of the compartment to prevent the body portion of the bottle moving inwardly 100 towards the axis of the carrier too far to permit the restraining devices controlling proper position of the bottles in the carrier, so that for bottles of this kind the caps may be at a greater distance from the axis of the carrier 105 than the inner edges of the disks 10 and 11.

The conical walls of the distended portions

12 and 13 have extending from them folded portions 15 and 16 to facilitate forming the bottle compartments, and these folded portions 15 and 16 extend a sufficient distance 5 from the compartments axially of the carrier so that their outer edges are nearly or quite in the plane of the outermost portions of the cylindrical parts of the bottle compartments. Each half of the carrier thus far described is 10 formed in the same way as the other half, by stamping and forming it from a single piece of sheet metal, so that both halves may be made by the same tools, and when the halves are thus formed, they are fastened together 15 in any suitable manner with the portions 12 and 13 opposite each other, for example by soldering, brazing, riveting, electric welding or in any equivalent manner.

The inner ends of the folded parts 15 and 16 20 of the portions 12 and 13, are secured in any desired manner, for example by soldering, brazing, riveting or electric welding to the outer portions of hub disks 17 and 18 of sheet metal, having central apertures for receiving 25 a sleeve 19 co-axial with the axis of the drum, to receive a suitable shaft to support the carrier for rotation. Between the disks 17 and 18, the sleeve 19 carries a second sleeve 20 which is shouldered at its mid portion to support 30 a stop disk 21 on it in a plane perpendicular to the axis of the carrier. The stop disk 21 is of an outer diameter substantially equal to the inner diameter of the formed disks 10 and 11, and serves to engage the bottle caps 35 when the bottles are of the long slender neck variety, to prevent the bottles moving inwardly in their compartments, too far to be properly controlled by the carrier. The hub disks 17 and 18 are preferably inturned adjacent 40 the sleeve 19 as indicated at 17^a and 18^a to facilitate securing the parts together since when soldering, brazing or welding material is employed, it will fill the recesses thus made and form a stronger union between the 45 parts than if the inner edge portions of the disks 17 and 18 were flat.

In co-pending application, Serial No. 220,896 above referred to, provision is made for mounting bottle carriers of the general 50 class above described, however they may be constructed, so that bottles contained in the carrier may be moved successively through the refrigerating zone of a bottle cooler and since the carrier described in the present application is intended for use in a bottle cooler of the kind shown in said co-pending application, the construction of such a cooler is not illustrated herein.

In Fig. 3 we illustrate diagrammatically 60 the use of the carrier shown in Figs. 1, 2 and 4. The carrier is filled with bottles 14, 14^a, which may or may not be all of the same variety. The carrier is mounted for rotation so that it is surrounded by a metal bar or rod 65 22 of semicircular formation, surrounding

the lower half of the carrier and at a distance from the axis of the carrier radially to just clear the bottoms of the bottles 14, 14^a. When the carrier is rotated with the bottles in the compartments, the rod or bar 22 prevents the bottles dropping from their compartments and causes them to travel with the carrier from one end of the rod or bar 22 to the other, the bottles of course remaining in the compartments through the upper half of the rotation of the carrier, by the action of gravity. It will be observed that there may be considerable latitude in the length of the bottles, without interfering with the operation of the carrier, as long as the bottom of the bottle 70 does not project from the carrier a greater distance than the distance of the rod or bar 22 from the carrier, and since bottles having a given liquid capacity are of substantially 75 the same diameter, although they may be of different shapes at their neck portions, the carrier is serviceable for bottles generally, regardless of the shape of their neck portions.

The size of the disks 10 and 11 is preferably 80 such that the bottle compartments lie closely adjacent to each other with their axes in radial lines of the carrier, to the end that as many bottles may be received by the carrier 85 as possible to increase the efficacy of the cooling operation.

In the construction shown in Fig. 5, we 90 employ modified hub disks 23 and 24, so formed that the stop disk 21 is no longer required, these disks 23 and 24 being formed at their outer edges with inwardly extending portions 23^a, 24^a, the outer walls of which are substantially cylindrical and terminate in flanges 23^b, 24^b for engaging the inner edges of the folded portions 15 and 16 of the 95 carrier disks. The extensions 23^a and 24^a extend towards each other sufficiently so that the space between them is less than the diameter of the caps used to seal the bottles handled by the carrier, and these extensions 100 therefore serve as a stop for bottles having long slender necks. With this construction we preferably employ a shouldered sleeve 105 25 co-axial with the carrier and extending through central apertures in the hub disks 23 and 24, to receive any desired supporting shaft. In this case as before, the parts of the carrier may be secured together in any convenient way above stated or otherwise.

It will be observed that the carrier shown 110 and described is of simple construction, that it is stiff and strong, and may be readily and cheaply made, besides serving effectively to hold bottles in radial positions with their necks innermost so that they may be moved angularly in substantially the same plane around the axis of the carrier.

While we have shown our invention in the particular embodiment above described, it 115 will be understood that we do not limit our 120

selves to this exact construction as we may employ equivalents known to the art at the time of the filing of this application without departing from the scope of the appended claims.

What we claim is:

1. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, a central bearing member, and devices supported by said member and secured to said disks to support them. 10
2. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks and to engage the inner ends of bottles in said compartments. 15
3. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation. 20
4. In a bottle carrier of the class described, the combination of two similarly formed sheets of metal having distended portions, said formed sheets being secured together in reversed relation with said distended portions in registry with each other to form bottle compartments, and means supporting said sheets for movement of said compartments through a desired zone. 25
5. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, said central members comprising similar central disks having formed cylindrical extensions projecting towards each other to engage the inner ends of said bottles and flanged to engage said first named disks. 30
6. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, each of said compartments being cylindrical at its outer end to receive part of the body portion of a bottle, and conical from said cylindrical portion to the inner end of said compartment to receive the entire neck portion of a bottle. 35
7. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, a central bearing member, and devices supported by said member and secured to said disks to support them, each of said compartments being cylindrical at its outer end to receive part of the body portion of a bottle, and conical from said cylindrical portion to the inner end of said compartment to receive the entire neck portion of a bottle. 40
8. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, a central bearing member, and devices supported by said member and secured to said disks to support them, each of said compartments being cylindrical at its outer end to receive part of the body portion of a bottle, and conical from said cylindrical portion to the inner end of said compartment to receive the entire neck portion of a bottle, each said conical portion having opposite folded portions extending outwardly therefrom, to facilitate forming said compartments and engage said supporting devices. 45
9. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, each of said compartments being cylindrical at its outer end to receive part of the body portion of a bottle, and conical from said cylindrical portion to the inner end of said compartment to receive the entire neck portion of a bottle. 50
10. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, each of said compartments being cylindrical at its outer end to receive part of the body portion of a bottle, and conical from said cylindrical portion to the inner end of said compartment to receive the entire neck portion of a bottle. 55

- metal having outwardly distended portions radially disposed and converging towards the axis of said disks, said disks being held together in reversed relation with said distended portions in alignment with each other to form bottle compartments, and central members supporting said disks for rotation, each of said compartments being cylindrical at its outer end to receive part of the body portion of a bottle, and conical from said cylindrical portion to the inner end of said compartment to receive the entire neck portion of a bottle, each said conical portion having opposite folded portions extending outwardly therefrom, to facilitate forming said compartments and engage said supporting devices.
11. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, said central members comprising similar central disks having formed cylindrical extensions projecting towards each other to engage the inner ends of said bottles and flanged to engage said first named disks, and a bearing member extending centrally through said central disks, each of said compartments being cylindrical at its outer end to receive part of the body portion of a bottle, and conical from said cylindrical portion to the inner end of said compartment to receive the entire neck portion of a bottle.
12. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, said central members comprising similar central disks having formed cylindrical extensions projecting towards each other to engage the inner ends of said bottles and flanged to engage said first named disks, each of said compartments being cylindrical at its outer end to receive part of the body portion of a bottle, and conical from said cylindrical portion to the inner end of said compartment to receive the entire neck portion of a bottle, each said conical portion having opposite folded portions extending outwardly therefrom, to facilitate forming said compartments and engage said supporting devices.
13. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, said central members comprising similar central disks having formed cylindrical extensions projecting towards each other to engage the inner ends of said bottles and flanged to engage said first named disks, and a bearing member extending centrally through said central disks, each of said compartments being cylindrical at its outer end to receive part of the body portion of a bottle, and conical from said cylindrical portion to the inner end of said compartment to receive the entire neck portion of a bottle.
14. In a bottle carrier of the class described, the combination of two similar disks of sheet metal having outwardly distended portions radially disposed and converging towards the axis of said disks, said disks being held together in reversed relation with said distended portions in alignment with each other to form bottle compartments, and central members supporting said disks for rotation, said central members comprising similar central disks having formed cylindrical extensions projecting towards each other to engage the inner ends of said bottles and flanged to engage said first named disks, and a bearing member extending centrally through said central disks, each of said compartments being cylindrical at its outer end to receive part of the body portion of a bottle, and conical from said cylindrical portion to the inner end of said compartment to receive the entire neck portion of a bottle, each said conical portion having opposite folded portions extending outwardly therefrom, to facilitate forming said compartments and engage said supporting devices.

In witness whereof, we hereunto subscribe our names this 3 day of November, A. D. 1927

JOHN M. SCHILLING.
WILLARD G. SCHILLING.
